Primary Examiner—A. Hugo Word*Assistant Examiner*—R. Seifert*Attorney, Agent, or Firm*—Ladas & Parry**[57] CLAIM**

The ornamental design for a safety strap for use with watches, compasses and depth gauges, as shown and described.

DESCRIPTION

FIG. 1 is a perspective view of a safety strap for use with watches, compasses and depth gauges in a buckled condition showing my new design;

FIG. 2 is a top plan view thereof;

FIG. 3 is a side elevational view, the other side being a mirror image thereof;

FIG. 4 is a front elevational view thereof;

FIG. 5 is a rear elevational view thereof;

FIG. 6 is a bottom plan view thereof; and

FIG. 7 is a perspective view thereof in an unbuckled condition.

FIG. 1

FIG. 2

FIG. 3

FIG. 4

FIG. 5

FIG. 6
